(Cl. D71—1)

To all whom it may concern:

Be it known that we, William K. Ebel and William A. Bortner, citizens of the United States and residents, respectively, of Kingsville, county of Baltimore, State of Maryland; and city of Baltimore, State of Maryland, have invented a new, original, and ornamental Design for an Airplane, of which the following is a specification, reference being had to the accompanying drawings, forming a part thereof.

Figure 1 is a perspective view of an airplane, showing the new design.

Figure 2 is a rear elevational view thereof.

Figure 3 is a top plan view thereof.

Figure 4 is a side elevational view thereof.

The characteristic features of our design re-

side in the portions shown in full lines in the drawings.

We claim:

The ornamental design for an airplane, substantially as shown and described.

WILLIAM K. EBEL.

WILLIAM A. BORTNER.
